UNITED STATES PATENT OFFICE.

JOHN H. KLINKEEMAN, OF CANTON, KANSAS, ASSIGNOR OF ONE-HALF TO JOHN A. ERICK, OF CANTON, KANSAS.

RADIATOR ATTACHMENT FOR TRACTOR.

Application filed October 22, 1924. Serial No. 745,200.

To all whom it may concern:

Be it known that I, JOHN H. KLINKERMAN, a citizen of the United States, residing at Canton, in the county of McPherson and State of Kansas, have invented certain new and useful Improvements in a Radiator Attachment for Tractors, of which the following is a specification.

This invention relates to an attachment for radiators of tractors and has for its principal object to provide a means whereby the consumption of water within the radiator will be reduced to a minimum.

A further object of the invention is to provide a radiator attachment of the above mentioned character which is adapted to be connected to the usual air washer tractor of the Fordson type whereby the steam from the attachment may be admitted to the air washer where part of it condenses with the water in the air washer and the vapor passes into the carburetor and becomes commingled with the gases before the same enter the intake manifold.

25 A further object of the invention is to provide an attachment of the above mentioned character, which is of such construction as to permit the same to be easily and readily placed in position on a tractor radiator and which will at all times be positive and efficient in carrying out the purposes for which it is designated.

30 A still further object is to provide a radiator attachment of the above mentioned character, which is simple in construction, inexpensive, strong and durable.

Other objects and advantages of this invention will become apparent during the course of the following description.

40 In the accompanying drawing forming a part of this specification and in which like numerals designate like parts throughout the same:

The figure represents a vertical sectional view of the attachment embodying my invention showing the same in position on the threaded neck of a tractor radiator.

In the drawing, wherein for the purpose of illustration is shown the preferred embodiment of my invention, the numeral 1 designates the cylindrical casing, the lower end of which is internally threaded as illustrated at 2 whereby the casing may be supported on the threaded neck 3 of the radiator.

45 The upper end of the cylindrical casing is externally threaded and provides a means for detachably receiving the cap 5.

Arranged within the cylindrical casing 1 and formed integrally therewith are a plurality of horizontally disposed baffle plates 6 or partitions designated by the numeral 6. Any number of these baffle plates or partitions may be provided as is desired, and the same are arranged in parallel spaced relation with respect to each other as is clearly illustrated in the drawing. A gasket 7 is interposed between the lowermost baffle plate or partition and the upper edge of the threaded neck 3 of the radiator to prevent leakage. Each of the baffle plates has an opening such as is indicated at 8 provided therein and the openings in the baffle plates are so arranged as to cause the steam to travel upwardly in the casing in a circuitous manner.

50 A vertical tube 9 extends centrally through the cylindrical casing 1 and through the baffle plates or partitions 6. The upper end of the tube 9 has a flange 10 formed thereon for engagement with the cap 5 forming an air tight joint, the lower end of the tube 9 extending through the lowermost baffle plate and into the top of the neck 3 of the radiator 4. The tube 9 is provided with an opening 11 which is arranged transverse to the bore of the tube and the same is formed adjacent the lower end of the same. The purpose of the opening 11 will also be hereinafter more fully described.

55 The cap 5 is provided with an outlet 12 over which is fitted one end of the rubber hose 13. The other end of the hose is adapted to be connected to the air washer (not shown) which is associated with the carburetor of the tractor in the well known manner.

60 With the attachment in position on the neck of the radiator in the manner shown in the drawing, and closing the usual overflow pipe, as the water becomes hot and starts to boil, the hot water and steam will rise upwardly into the central tube 9 in the direction of the arrows and upon reaching the

upper end of the tube which is closed by the cap 5, the water will return to the radiator while the steam will follow the direction of the arrows and leave the tube at the opening 11. The steam entering the casing 1 from the opening 11 in the lower end of the tube 9 will pass upwardly in a circuitous manner. The openings 8 in the baffle plate or partition 6 are so arranged as to cause the steam to pass upwardly through the casing in the direction of the arrows. During the upward flow of the steam, the water will drip back onto the baffle plates and finally be returned to the radiator. The steam will leave the casing through the outlet 12 in the top of the same and will enter the rubber hose 13 where it is caused to flow into the air washer (not shown). A portion of the steam will be condensed and the balance of the steam will pass into the carburetor where it becomes commingled with the gases before the latter enter the intake manifold. This will increase the efficiency in the operation of the internal combustion engine of the tractor as well as reduce the consumption of fuel.

It will thus be seen from the foregoing description that an attachment for tractor radiators has been provided wherein the consumption of water in the radiator is reduced to a minimum and the device is of

such construction as to at all times be positive and efficient in its operation.

While I have shown the preferred embodiment of my invention, it is to be understood that various changes in the size, shape and arrangement of parts may be resorted to without departing from the spirit of the invention and the scope of the appended claim.

Having thus described the invention, what I claim is:

A radiator attachment comprising a cylindrical open ended casing screw threaded at its opposite ends, the lower end being adapted to be secured to a radiator filler tube, a plurality of superposed vertically spaced partitions arranged horizontally within the casing, the end most partition being spaced inwardly from the ends of said casing, all of said partitions being provided with central aligned holes and with auxiliary openings arranged in staggered relation, an open ended vertical tube extending through the central holes in said partition, a closing cap screwed on the upper threaded end of said casing and closing the adjacent end of said tube, said cover being provided with a discharge neck for attachment of a steam conducting conduit.

In testimony whereof I affix my signature.

JOHN H. KLINKERMAN.
